(57) **CLAIM**

The ornamental design for a display screen or portion thereof with an animated graphical user interface, as shown and described.

DESCRIPTION

FIG. 1 is a front view of a display screen or portion thereof with a first image of an animated graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is an enlarged portion of the first image taken from the area labeled 7 in FIG. 1;

FIG. 8 is an enlarged portion of the second image taken from the area labeled 8 in FIG. 2;

FIG. 9 is an enlarged portion of the third image taken from the area labeled 9 in FIG. 3;

FIG. 10 is an enlarged portion of the fourth image taken from the area labeled 10 in FIG. 4;

FIG. 11 is an enlarged portion of the fifth image taken from the area labeled 11 in FIG. 5; and,

FIG. 12 is an enlarged portion of the sixth image taken from the area labeled 12 in FIG. 6.

The subject matter in this patent includes a process or period in which an image changes into another image. This process or period forms no part of the claimed design.

The outermost broken lines shown in the drawings represent the display screen or portion thereof with an animated graphical user interface that form no part of the claimed design. The broken lines in the animated graphical user interface illustrating portions of the graphical user interface form no part of the claimed design.
